Patented Aug. 22, 1922.

UNITED STATES PATENT OFFICE.

GEORGE S. RESSLER, OF LANSING, MICHIGAN.

VEHICLE LAMP DIMMER.

1,426,774.

Specification of Letters Patent. Patented Aug. 22, 1922.

Application filed January 24, 1921. Serial No. 439,356.

To all whom it may concern:

Be it known that I, GEORGE S. RESSLER, a citizen of the United States of America, residing at Lansing, in the county of Ing-
ham and State of Michigan, have invented
5 certain new and useful Improvements in
Vehicle Lamp Dimmers, of which the fol-
lowing is a specification, reference being had
therin to the accompanying drawings.

10 The invention relates to devices used in
connection with vehicle headlights, for the
purpose of preventing glare, and the inven-
tion consists in a novel construction readily
15 attachable to the headlights of any vehicle
and which effectively accomplishes the pur-
pose.

In the drawings:

Figure 1 is a perspective view showing my
attachment applied to the headlights of a
20 vehicle;

Figure 2 is a sectional side elevation;

Figure 3 is a front elevation, partly in
section;

Figure 4 is a sectional view showing a
25 modified construction.

In the mounting of headlights upon ve-
hicles it is usual to attach the same rigidly
to the chassis frame by suitable brackets,
but the size of the lamps varies with differ-
30 ent vehicles and also the spacing therebe-
tween. It is one of the features of my in-
vention to provide a supporting frame for
my dimmer which is engageable with the
35 lamps of any vehicle without regard to the
size or spacing thereof. This frame con-
sists, essentially, in a pair of shoes A and
A' of segmental and concaved form adapted
40 to embrace the rounded rim of a vehicle
lamp. These shoes are rigidly secured to
rod sections B and B', which are telescopi-
cally engaged with each other and within
45 the outer tubular section B' there is a spring
C for pressing the inner section B longi-
tudinally outward. The proportion of parts
is such that the rods may be collapsed to
50 engage lamps, which are spaced nearest to
each other, while the expansion of the spring
will bring the shoes in contact with lamps
more widely spaced. In each case the ten-
55 sion is sufficient to firmly hold the shoes
against the lamp rim and thereby to hold
the rods in fixed position. However, if de-
sired, a set-screw D or other clamping means
may be employed for locking the rods after
55 they have been once adjusted.

Extending upward from the rod B' are

arms E and at the upper ends of these arms
are bearings F for a rock shaft G. This
rock shaft is tubular and has telescopically
engaged therewith extension sections H and 60
H' which are held in different positions of
adjustment by set-screws I. These set
screws also preferably pass through collars
J, which are located adjacent to the arms
E and hold the rock shaft G from longi- 65
tudinal displacement. K and K' are shields
mounted at the outer ends of the extension
rods H and H', said shields being prefer-
ably circular and of a size to obstruct the
70 rays from the lamps when in registration
therewith. Each shield is also formed with
a series of louvers L, which, when the shield
is in oblique position, permit the passage of
rays of light therethrough in a horizontal 75
or downwardly inclined direction, but inter-
fere with the passage of upwardly inclined
rays. The shields K and K' are normally
held in down-turned position by means of
80 a spring M, one end of which is anchored
to an arm N clamped upon the rod B', while
the outer end is attached to a rock arm O
on the rock shaft G. This rock arm is pref-
erably in the form of a bell-crank lever, the 85
opposite arm P of which is attached to a
rod or flexible connection Q leading to a
point under the control of the driver. Thus,
whenever the rod Q is actuated, the rock
shaft G is tilted to turn up the shields K 90
and K', but when said rod is released, the
tension of the spring M will at once pull the
shields downward. When in downturned
position, indicated in dotted lines in Fig-
95 ure 2, sufficient light from the lamp will
pass through the louvers L to illuminate
the road immediately in front of the vehicle,
but when the shields are turned upward, the
road is illuminated for a much greater dis- 100
tance in advance. It is possible, however,
to so limit the upper angle of adjustment
that all rays which would cause an objec-
tionable glare are prevented.

With the construction as described, to ap-
ply the same to the vehicle, it is only neces-
sary to compress the spring C so as to con-
tract the length of the telescopic rods B and
105 B' a sufficient amount to engage the shoes
A and A' with the rims of the vehicle lamps.
When released, the spring C will force these
shoes firmly in contact with said rims and
the rod may then be locked by the set screw 110
D. To prevent marring of the lamp rim,
the shoes are padded on their inner faces

with felt or other suitable material, as indicated at R. To permit of engagement with lamps of different diameters, the shoes are of a curve to fit the smallest sized lamp and have the outer end portions of somewhat different curve for engaging larger lamps. An alternative construction is shown in Figure 4, in which in place of the shoes A and A' a T-head S is arranged at the ends of the telescopic rods B and B' and to each end of each of these heads is loosely attached a short shoe T. These shoes are capable of a limited rocking movement, and therefore will adjust themselves to any arc according to the size of the lamp rim.

When the device is installed, the operator is enabled to adjust the shields according to conditions and when in the lowest position of adjustment, there is still sufficient light passing through the louvers to illuminate the road immediately ahead.

What I claim as my invention is:

1. A dimmer for headlights, comprising a longitudinally collapsible frame, shoes at the opposite ends of said frame for engaging the headlights, a rock shaft mounted in said frame, and shields secured to said rock shaft and movable in relation to said headlights.

2. A dimmer for headlights, comprising a telescopic rod, shoes at the opposite ends of said rod for engaging the headlights, means for resiliently expanding said telescopic rod to hold said shoes in engagement, arms extending upward from said rod, a rock shaft journaled in said arms, shields mounted on said rock shaft in registration with said headlights, and means for rocking said shaft to tilt said shields in relation to said lamp.

3. A dimmer for vehicle headlights, comprising a frame longitudinally adjustable, shoes at opposite ends of said frame for engaging the headlights, a rock shaft journaled in said frame and longitudinally adjustable extensions at the ends of said rock shaft, and shields mounted on said extensions and registrable with said lights, differently spaced from each other.

4. A dimmer for headlights, comprising a frame including a tubular rod, a segmental shoe at the end of said rod for engaging one of a pair of vehicle headlights, a rod telescopically engaging said tubular rod and

provided with a segmental shoe for engaging the other of the pair of headlights, a spring within said tubular rod for yieldably pressing the telescopic rod outward, a rock shaft mounted on said frame, and shields mounted on said rock shaft registrable with said headlights.

5. A dimmer for vehicle headlights, comprising a frame including a tubular rod, a segmental shoe at the end of said rod concaved to fit over the rim of a vehicle headlight, a rod telescopically engaging said tubular rod, a similar shoe at the end of said last-mentioned rod for engaging the opposite headlight, a spring within said tubular rod for yieldably moving said telescopic rod outward, a rock shaft journaled in said frame, telescopic extensions at the ends of said rock shaft, and shields carried by said telescopic extensions registrable with the headlights.

6. A dimmer for headlights, comprising a frame including a tubular rod, a rock telescopically engaging said tubular rod, a spring within said tubular rod for yieldably pressing the telescopic rod outward, segmental shoes at the opposite ends of said rods concaved to embrace the rims of vehicle headlights, arms extending upward from said tubular rod having journal bearings at their upper ends, a tubular rock shaft journaled in said bearings, extensions at the ends of said rock shaft telescopically engaging the same, shields on said extensions registrable with said headlights a bell-crank lever mounted on said rock shaft a spring connected to one arm of said bell-crank lever, an anchor for the opposite end of said spring clamped to said tubular rod, and an operating connection attached to the opposite end of said bell crank lever.

7. A dimmer for head-lights, comprising an extensible frame, gripping means at the ends of said frame for engaging the headlights, shields for said head-lights, and means mounted upon said frame for rocking said shields in relation to said headlights.

In testimony whereof I affix my signature.

GEORGE S. RESSLER.
